UNITED STATES PATENT OFFICE.

WILLIAM GEORGE BEATTY, OF FERGUS, ONTARIO, CANADA.

WRINGER.

Application filed November 30, 1926. Serial No. 151,806.

According to my invention the water from the wringer is discharged into a spout constructed with two water chutes, each set in an opposite direction to the other, for delivering it to the corresponding side of the wringer, and this spout is adjustable lengthwise of the wringer rolls for bringing either chute into position to receive the discharge.

Various modifications of the structural details are within the scope of the invention and in one embodiment of the invention the bottom of the wringer frame, or that part of it below and extending lengthwise of the rolls, is of a trough shaped formation and has a drainage orifice interjacent its ends and in another embodiment of the invention the wringer is provided with a trough separate from the frame and this trough is located below the rolls and extends lengthwise of them.

In both embodiments of the invention the under side of the frame or trough is formed with a slideway arranged lengthwise of the rolls and the spout is adjustable in this slideway to bring either selected chute into position below the discharge orifice.

For an understanding of the invention reference is to be had to the following description and accompanying drawings, in which:

Fig. 1 is a fragmentary perspective view of a wringer frame showing the movable spout, and

Fig. 2 is a perspective view of the movable spout.

Fig. 3 is a perspective view of a wringer showing the trough below the wringer rolls as forming part of the wringer frame, and Fig. 4 is a similar view to Fig. 3 showing the trough bolted to the wringer frame below the rolls.

Like characters of reference refer to like parts throughout the specification and drawings.

The bottom 56 of the wringer frame is of a trough shaped formation, as shown in Fig. 1 for collecting the water from the wringer rolls 71, and centrally formed through the trough or bottom of the frame is a discharge aperture 57. Beneath the trough or bottom of the frame is a slideway 58 and movable lengthwise of the slideway is an adjustable spout 59. This spout 59 has two separate and oppositely inclined water chutes 60 and 61, for delivering the discharge from the orifice or aperture 57 to either selected side

of the wringer. Beneath the movable spout 59 is a double inclined tray or table 62 extending beyond each side of the wringer to carry the water back to the container from which the clothes are being wrung and to guide the clothes into the next container. On the ridge of the tray or table 62 is a vertical fin 63 which enters a groove 64 in the under side of the spout 59, and assists the slideway 58 in maintaining the movement of the spout in a fixed path as the water chutes 60 and 61 are selectively brought into discharge relation with the orifice or aperture 57. The water chutes 60 and 61 discharge in opposite directions and it is possible by the use of a movable spout having water chutes arranged in this way to reverse the direction of the flow of the water which collects in the bottom of the wringer frame and by delivering the discharge to a double inclined tray or table to direct the water back into the container from which it came.

Instead of forming a trough at the bottom of the wringer frame, the trough 70 may be made separate from the frame, and bolted to it beneath the wringer rolls 71 as shown in Fig. 4, and extends lengthwise of the wringer rolls. The under side of the trough is formed with a slideway extending lengthwise of the wringer rolls and the spout is movable lengthwise of the slideway and is conveniently manipulated by a laterally projecting lug 72.

Having thus fully described my invention what I claim as new and desire to secure by Letters Patent is:

1. A wringer comprising a wringer frame, wringer rolls therein, a drainage orifice at the bottom of the frame, and an adjustable spout having two water chutes set in opposite directions for delivering the discharge from the orifice at either selected side of the wringer, movable lengthwise of the rolls to bring either chute into operative relation with the orifice.

2. A wringer comprising a wringer frame, wringer rolls therein, a drainage orifice at the bottom of the frame and an adjustable spout beneath the frame, movable lengthwise of the rolls and having two water chutes set in opposite directions, either of which may, by the lengthwise adjustment of the spout, be moved into operative relation with the orifice for delivering the discharge from the orifice at either selected side of the wringer.

3. A wringer comprising a wringer frame,

wringer rolls therein, a trough beneath and extending lengthwise of the rolls, a discharge orifice for the trough, and an adjustable spout below the trough having two water chutes set in opposite directions and movable lengthwise of the rolls to bring either chute into operative relation with the discharge orifice.

4. A wringer comprising a wringer frame, wringer rolls therein, a trough beneath and extending lengthwise of the rolls, a discharge orifice for the trough, an adjustable spout below the trough having two separate water chutes set in opposite directions which by selective adjustment delivers the discharge from the orifice at either selected side of the wringer, and a double inclined drainboard with its ridge beneath the trough for receiving the discharge from the spout, said spout being movable lengthwise to bring either chute into operative relation with the orifice.
5. A wringer comprising a wringer frame, wringer rolls therein, a trough beneath and extending lengthwise of the rolls, a discharge orifice for the trough, a spout movable lengthwise of the wringer rolls having two separate

water chutes set in opposite directions either of which may, by the adjustment of the spout, be moved into operative relation with the orifice for delivering the discharge at either selected side of the wringer, and a double inclined drainboard with its ridge beneath the trough for receiving the discharge from the spout, said spout being movable lengthwise of the wringer rolls to bring either chute into operative relation with the orifice.

6. A wringer as claimed in claim 1 in which a slideway is provided beneath the frame and the spout is movable in this slideway lengthwise of the rolls.

7. A wringer as claimed in claim 4 in which a slideway is provided beneath the trough and the ridge of the tray is provided with a fin which enters a corresponding groove in the spout for guiding the movement of the spout lengthwise of the rolls.

Dated at the town of Fergus, in the county of Wellington and Province of Ontario, Dominion of Canada, the 30th day of October, 1926.

WILLIAM GEORGE BEATTY.
